UNITED STATES PATENT OFFICE.

GUSTAVE FREDERICK HITZELBERGER, OF LONDON, ENGLAND, ASSIGNOR TO AMERICAN EVER READY COMPANY, A CORPORATION OF NEW YORK.

PORTABLE ELECTRIC LIGHT.

1,205,628.

Specification of Letters Patent. Patented Nov. 21, 1916.

Application filed March 9, 1914. Serial No. 823,300.

To all whom it may concern:

Be it known that I, GUSTAVE FREDERICK HITZELBERGER, a citizen of the United States, residing at London, England, have invented 5 certain new and useful Improvements in Portable Electric Lights, of which the following is a specification, reference being had therein to the accompanying drawings, forming part thereof.

10 My invention relates to portable electric lights of such size and proportions as to be suitable for conveniently carrying from place to place and standing upon any flat surface, as upon a table or mantel, lights of 15 this general kind being popularly known as "electric candles."

Objects of my invention are simplicity of construction, inexpensiveness of manufacture, durability, neatness of appearance, 20 certainty of retention of the closed circuit and the open circuit conditions, certainty of operation and of operable condition, and convenience of operation.

Other objects are facility of assembling 25 and of renewal of parts, should such become necessary.

Another object is that the device may be readily constructed in different heights, to represent candle-sticks of corresponding 30 variations in height.

Other objects and advantages of my invention will hereinafter appear.

My invention includes features of construction and combinations of parts, as will 35 appear from the following description.

I shall now describe the portable electric light illustrated in the accompanying drawings embodying my invention and shall thereafter point out my invention in claims.

40 Figure 1 is a central vertical section, partly in elevation, with the circuit in the open condition. Fig. 2 is a similar enlarged view in further section of some of the parts appearing in Fig. 1. Fig. 3 is a similar

45 view with the circuit in the closed condition. Fig. 4 is a vertical section on planes indicated by line 4-4 of Fig. 3 as viewed from the right. Fig. 5 is a horizontal section on a plane indicated by line 5-5 of Fig. 3 as viewed from below. Fig. 6 is an elevation, partly in section, of the circuit-completing post and its adjuncts.

The portable electric light illustrated in the drawings has the general appearance of 55 a candle-stick holding a candle. It has a

tubular sheet metal column, which includes an upper part 1 representing a candle and a lower part 2 representing a candle-stick and provided with a weighted flaring base and an upper flange, as shown. The upper 60 and lower parts 1 and 2 are shown as screwed together. The upper end of the tubular part 1 is provided with a lamp-receiving socket 3, into which is screwed a miniature incandescent lamp 4. The two- 65 part tubular column removably contains a cylindrical battery 5 having a battery terminal 6 central of the top in position to be directly engaged by the center terminal of the lamp 4, the lamp forming an electrical 70 connection between its socket 3 and the battery terminal 6. The sheet metal casing 7 of the battery is exposed at the bottom of the battery and forms the other battery terminal. Electrical connection between the 75 battery terminal 7 and the lower part 2 of the conductive column is controlled by the circuit closer of my present invention.

A circuit-completing rod or post 8 is secured by means of a supporting screw 9 to a cup-shaped insulating plug or block 10 fitting snugly into the lower cylindrical end of the lower tubular column part 2 and provided with a slight flange to limit its entrance into the tubular part 2. The post 8 extends upward within the lower portion of the tubular part 2 and at its upper end has an electrically conductive disk 11 secured thereto by means of a fastening screw 12, which also holds in place a non-conductive 90 insulating and spacing disk 13. A spiral spring 14, having its larger end soldered to the upper surface of the metal disk 11, yieldingly supports the battery 5 upon its upper and smaller end and constitutes also a resilient contact terminal which makes electrically conductive connection with the battery terminal 7.

The insulating plug 10 carries a stationarily mounted contact member 15 shown as a reversely bent leaf spring substantially of a narrow V-shape having one of its legs secured to the lower end of the post 8 and to the insulating plug 10 by the supporting screw 9, which also electrically conductively 105 connects the contact member 15 to the post 8.

The movable parts of the circuit closer include an insulating member 16 and a contact piece 17, which are shown as of trans- 110

versely circular tubular form having larger abutting ends of the same diameter. The contact piece 17 forms part of a movable circuit-closing member having joined metal stems 18 and 19. The stem portion 18 of the circuit-closing member has a reduced portion screwed into the end of the other stem portion 19, providing opposed shoulders between which the tubular insulating member 16 and the tubular contact piece 17 are clamped together on the reduced middle portion of the circuit-closing member.

Registering or alined apertures are shown as provided in opposite sides of the lower tubular column part 2 adjacent to its flared base and in the opposite sides of the cup-shaped insulating plug 10, and the stems 18 and 19 pass through these alined openings, so that the insulating plug 10 is held in place in the tubular column part 2 by the stems 18 and 19 of the circuit closer, and the stems 18 and 19 are in electrically conductive connection with the lower column part 2. The movable insulating member 16 and the movable contact piece 17 are in co-operative relation with the stationarily mounted contact member 15 within the cup of the insulating plug 10. The contact spring 15 is curved adjacent to its free end to provide a rounded or convex portion which, by reason of the spring action of the contact spring 15, is pressed against and into frictional engagement with the movable contact piece 17 or the movable insulating member 16, according to the position of the circuit-closing member, the stems 18 and 19 of which are free to slide longitudinally through the apertures in the tubular part 2 and insulating plug 10. The slideable stems 18 and 19 are shown as provided at their exposed ends with finger knobs, and by pressing upon the one or the other of the knobs, either the contact piece 17 or the insulating member 16 may be brought into engagement with the rounded free end portion of the contact spring 15, which extends in the same direction as the stems 18 and 19. The frictional engagement of the contact spring 15, assisted by the tapered form of the movable insulating member 16 and of the movable contact piece 17, will securely maintain the circuit in the open condition shown in Figs. 1 and 2, or in the closed condition appearing in Figs. 3, 4 and 5. The circular cross-section of the tubular tapered insulating member 16 and contact piece 17 permits rotative shifting movements of these parts, together with the cylindrical stems 18 and 19, thereby widely distributing the wear of use, and also the construction is very inexpensive to make.

It will be noted that the contact spring 15 and the spring contact terminal 14 co-operate to produce firm contact-making engagement of the metal stems 18 and 19 with

the metal tube 2 and also to hold up the battery 5 with its center terminal 6 in firm engagement with the center terminal of the lamp 4. It will be further noted that it is a very simple matter to make the circuit-completing post 8 of any suitable length, either longer or shorter than appears in the drawings, to readily accommodate the circuit closer of my invention to lights in which the column, shown as made up of the tubes 1 and 2, may be of a different length, longer or shorter, than that shown in the drawings, and still have the finger-actuated stems 18 and 19 in proximity to the base of the light, where they will be most convenient for use, out of the way and also give a neater appearance.

It is obvious that various modifications may be made in the construction shown in the drawings and above particularly described within the principle and scope of my invention.

I claim:

1. A circuit closer for a portable electric light comprising, in combination, a tubular supporting column of electrically conductive material having apertures therein at opposite sides of the column, an electrically conductive circuit-closing member slideable through the apertures in electrically conductive connection with the column and including portions joined together to provide shoulders, a contact piece and an insulating member both clamped between the shoulders of the circuit-closing member and movable therewith, an insulating plug held in place within the tubular conductive column by the slideable circuit-closing member, a resilient contact member carried by the insulating plug and engageable with the contact piece and with the movable insulating member to maintain the closed circuit or the open circuit condition according to the position of the slideable circuit-closing member, a circuit-completing post carried by the insulating plug in electrically conductive connection with the resilient contact member and projecting upward within the tubular conductive column, a spacing disk of insulating material carried by the post in spaced relation to the insulating plug, and a resilient contact terminal projecting upward from the upper end of the post in electrically conductive connection therewith.

2. A circuit closer for a portable electric light comprising, in combination, a tubular supporting column of electrically conductive material having apertures therein at opposite sides of the column, an electrically conductive circuit-closing member slideable through the apertures in electrically conductive connection with the column, an insulating plug held in place within the tubular conductive column by the slideable circuit-closing member, an insulating member car-

ried by the slidable electrically conductive circuit-closing member to move therewith within the tubular conductive column, a spring-pressed contact member carried by the insulating plug and engageable with the slidable circuit-closing member and the movable insulating member to maintain the closed circuit or the open circuit condition according to the position of the slidable circuit-closing member, a circuit-completing post carried by the insulating plug in electrical connection with the spring-pressed contact member and projecting upward from such plug within the tubular conductive column, and a contact spring carried by the upper end of the post.

3. A circuit closer for a portable electric light comprising, in combination, a tubular supporting column of electrically conductive material having apertures therein at opposite sides of the column, an insulating block of cup shape in the tubular conductive column having opposite apertures therein in registry with the apertures of the column, an electrically conductive circuit-closing member in electrically conductive connection with the column and slidable through

the alined apertures in the column and block and holding the latter in place in the former, such circuit-closing member having stem 30 portions joined together to provide a middle reduced portion between opposite shoulders within the cup-shaped insulating block, a contact piece and an insulating member on the reduced portion of the circuit-closing 35 member and clamped between the shoulders thereof, a circuit-completing post carried by the insulating block and projecting upward within the tubular conductive column, a spring-pressed contact member secured to 40 the lower end of the post and having engagement with the contact piece and the insulating member to maintain the closed circuit or the open circuit condition according to the position of the circuit-closing member, and a spring-pressed contact terminal carried by the upper end of the post.

In testimony whereof I have affixed my signature in presence of two witnesses.
